UNIT-TYPE FLUSH BOX AND TOILET
CONSTRUCTION

Stanley S. Lenski, La Salle, Ill.

Application February 5, 1947, Serial No. 726,543

1 Claim. (Cl. 4—12)

1

This invention relates to new and useful improvements in unit-type toilets of the type where in the toilet is provided with a rearwardly extending shelf to which a flush tank is rigidly secured.

The main objects of this invention are to provide a device of this character embodying a novel construction and arrangement whereby dripping of condensation from the flush tank to the floor or other surfaces will be prevented; to provide in a device of this character means for directing the flow of condensation directly into the toilet bowl; to provide a device of this character which is highly efficient and reliable and all formed at the same time the unit-type toilet is constructed, whereby no additional parts are required other than those normally used in forming a unit-type toilet; and to provide a device of this character which is attractive in appearance and may be manufactured at small additional cost, over the normal cost of unit-type toilets.

An illustrative embodiment of this invention is shown in the accompanying drawings in which:

Figure 1 is a side elevational view of the device of my invention.

Fig. 2 is a top elevational view taken on the line 2—2 of Fig. 1.

Fig. 3 is a front elevational view taken on the line 3—3 of Fig. 1, part of the toilet being shown in section.

Fig. 4 is a sectional view taken on the line 4—4 of Fig. 2.

Fig. 5 is a bottom view of the flush box removed from the toilet.

Fig. 6 is a cross-sectional view taken on the line 6—6 of Fig. 2.

Referring to the drawings in detail, the flush box or tank 11 is in the main of the usual form and shape, having a front wall 12, end walls 13 and 14, a back wall 15 and a bottom wall 16 which is slightly rounded and tapered as shown especially in Figs. 1 and 3, both from the rear wall 15 to the front wall 12, and from the end walls 13 and 14 to the marginal edges respectively of the bearing or supporting area or surface 17.

As is apparent from the drawings, the upper portion of the box 11 is substantially rectangular while the side or end walls 13 and 14 and the back wall 15 of the lower area, that is the area below, substantially the horizontal center line of the box, converges downwardly toward the vertical center line of the front wall and terminates at the marginal edges of the bearing surface 17.

The toilet is of the usual construction having a bowl area 18, a base 19, a water course 20 and an

2

integrally formed rearwardly extending shelf 21 lying in the same plane as the top surface of the bowl area 18, having an inlet port 22 therein communicating in the usual manner with the water course 20. The water course 20 is also provided with the usual spaced outlet ports 23.

The shelf 21 is formed with a pair of spaced channels 24 and 25, closed at the rear end, and the forward ends opening into and blending with the upper rear end of the toilet bowl area 18. As will be apparent from Fig. 2, the shelf has four flush box or tank bearing surfaces or supporting areas 26, 27, 28 and 29 respectively. The bowl water inlet port 22 is located in the bearing surface 27 while each of the bearing surfaces 26 and 28 are provided with bolt-receiving apertures 30 and 31 which are aligned with similar apertures in the bottom wall 16 of the tank for bolting the tank 11 to the shelf 21 in the usual manner as will be understood by those skilled in the art. Similarly, the tank 11 is provided with an outlet port located medially in the base area 17 and is aligned with and communicates with the inlet port 22 of the toilet.

As shown in the drawings, the base area seats on and slightly overlaps the supporting surface 27 whereby the marginal edges of the base area 17 are positioned directly over the channels 24—25.

It will now be apparent that when any condensation forms on the outer surface of the tank, it will flow downwardly along the walls by gravity to the base area 17, where the condensation will drip into the channels 24—25 and be conducted thereby into the toilet bowl area 18.

Although but one specific embodiment of this invention is herein shown and described, it will be understood that numerous details of the structure shown may be altered or omitted without departing from the spirit of the invention as defined by the following claim.

I claim:

In a unit-type toilet and flush box construction comprising a flush box having front, back and side walls, said box being substantially rectangular in its upper portion, the side walls of the lower portion thereof converging downwardly toward the vertical center line of the tank the back wall including a forwardly inclined surface terminating at the front wall and having a flat bearing area thereon; a toilet bowl having a rearwardly extending shelf disposed in the same plane as the top surface of said bowl, said shelf being provided with spaced channels in its upper surface leading into said bowl, means to rigidly secure said box on

said shelf, and aligned communicating ports in
said bearing area of said box and said shelf.

STANLEY S. LENSKI.
